UNITED STATES PATENT OFFICE

160,877

EXPANDED METAL PANEL

Charles L. Moorman, Millington, Ill.

Application May 7, 1948, Serial No. 146,214

Term of patent 14 years

(Cl. D54—2)

To all whom it may concern:

Be it known that I, Charles L. Moorman, a citizen of the United States and a resident of Millington, in the county of Kendall and State of Illinois, have invented a new, original, and ornamental Design for an Expanded Metal Panel, of which the following is a specification, reference being had to the accompanying drawing, forming a part thereof, and in which:

Fig. 1 is a top plan view of an expanded metal panel showing my new design;

Fig. 2 is an edge view of the same.

I claim:

The ornamental design for an expanded metal panel, as shown.

CHARLES L. MOORMAN.
